United States Patent

Des. 238,784
Patented Feb. 10, 1976

238,784

FIREPLACE OR SIMILAR ARTICLE

Donald L. Wescott, Rte. 12, Sherburne, N.Y. 13460

Filed Dec. 30, 1974, Ser. No. 537,437

Term of patent 7 years

Int. Cl. D23—03

U.S. Cl. D23—97

FIG. 1

FIG. 2

FIG. 3

FIG. 4

FIG. 5

FIG. 6

FIG. 1 is a top plan view of a fireplace or similar article showing my new design;

FIG. 2 is a front elevational view, the screen pattern which is partially shown is understood to repeat uniformly across the area;

FIG. 3 is a bottom plan view;

FIG. 4 is a rear elevational view;

FIG. 5 is a left elevational view taken from the left of FIG. 2; and

FIG. 6 is a side elevational view taken from the right of FIG. 2.

I claim:

The ornamental design for a fireplace or similar article, substantially as shown and described.
